HENRY F. BECHMAN, OF BATTLE CREEK, MICHIGAN, ASSIGNOR TO DUPLEX PRINTING PRESS COMPANY, OF BATTLE CREEK, MICHIGAN.

STEREOTYPE-PLATE FASTENING FOR ROTARY CYLINDER PRINTING-PRESSES.

1,129,946.

Specification of Letters Patent. Patented Mar. 2, 1915.

Application filed August 15, 1906. Serial No. 330,698.

To all whom it may concern:

Be it known that I, HENRY F. BECHMAN, of Battle Creek, in the county of Calhoun and State of Michigan, have invented certain new and useful Improvements in 5 Stereotype-Plate Fastenings for Rotary Cylinder Printing-Presses; and I hereby declare that the following is a full, clear, and exact description thereof, reference being had to the accompanying drawings, which form part of this specification.

This invention is an improvement in rotary cylinder printing presses, and has particular reference to the relative construction 15 of the cylinder and plates and the mode of securing the plates thereto.

The object of the invention is to reduce the diameter of the printing or plate cylinders and use single tubular plates thereon, 20 such plates being substantially the same in diameter as the cylinders and fitted thereto, each plate substantially surrounding the cylinder, and at each revolution of the cylinder but one plate will be printed circumferentially of the cylinder. Of course the cylinder may be of such length that a series 25 of plates may be arranged end to end on the same cylinder. The peculiar characteristic feature of this part of the invention is that 30 each plate constitutes almost a complete tube and must be slipped endwise, on or off, the cylinder, such cylinders being notably different from those ordinarily employed, which are somewhat less than half the 35 diameter of the cylinder in extent, and heretofore the cylinders have necessarily been somewhat more than twice the length of the plates in circumference and two sets of stereotype plates are secured to each cylinder 40 at diametrically opposite points,— whereas in my invention each stereotype plate is made in substantially tubular form, and substantially surrounds the entire circumference of the cylinder to which it is 45 applied.

While the peripheral speed of the cylinders, in my invention, is equal to that of the ordinary plate cylinders, the diameter of the plate cylinders is reduced one-half and 50 their weight is correspondingly lessened; and a corresponding reduction is made in the size of the press. The improved plate cylinders are provided with novel locking devices for fastening the plates thereto as 55 hereinafter described.

The essential features of the invention, and parts for which protection is desired, are summarized in the claims following the description of the mechanism illustrated in the drawings, in which—

Figure 1 is a side elevation of a cylinder carrying two of my tubular plates; Fig. 2 is a detail section thereof on line 2—2, Fig. 1; Fig. 3 is a left-hand end view; Fig. 4 is a transverse section on line 4—4, Fig. 1; Fig. 5 is a view of right-hand end; Fig. 6 is an enlarged detail view of the plate securing devices; and Fig. 7 is a vertical section on line 7—7, Fig. 6.

The cylinder 1 may be of any suitable 70 construction, and is substantially like the ordinary plate cylinders, with the exceptions hereinafter noted, but it is only half the diameter of the ordinary plate cylinders, and it is provided at one end with a 75 fixed collar 1^a, which is preferably beveled on its inner face and against which the oppositely beveled edge of one of the novel stereotype plates 2 is abutted. The cylinder is provided at the other end with novel plate 80 retaining devices hereinafter explained.

Each stereotype plate 2, it will be observed, is substantially tubular in contour, and of the same internal diameter as the external diameter of the cylinder 1, onto 85 which it is slipped endwise. The type columns on the plates 2 extend circumferentially thereof. The plates 2 are provided with beveled edges 2^a on their ends to engage the collar 1^a and the plate-securing clamps 90 hereinafter referred to.

One of the plates has its beveled edge 2^a engaged with the collar 1^a, and its inner beveled edge is engaged by clamps 3, which are slidable in longitudinal grooves 1^c, in 95 the cylinder 1, said grooves extending from the end opposite collar 1^a, to a point a little beyond the center of the cylinder, as indicated in Fig. 1. The grooves 1^c are dovetailed or T-shaped in cross-section, as shown, 100 and the clamps 3 are preferably provided with T-shaped bases biting the grooves so that the clamps cannot escape therefrom, but are adjustable longitudinally thereof. There are three grooves 1^c shown and the 105 clamps 3 are the central clamps, and are beveled on both edges to engage adjacent plates, as shown. After the first plate is put in place against collar 1^a, the clamps 3 are moved up thereagainst and then the next 110

plate 2 is slipped on to the cylinder and up against the clamps 3. Then end clamps 4,--which are provided with projecting edges to engage the beveled edge of the cylinder,—are slipped into grooves 1^a, and slid up against the edge of the outer plate, as shown in Figs. 1 and 7, so as to force the second plate toward the first plate and the first plate against the collar 1^a, and thus the 10 clamps hold both plates in position upon the cylinder. Rotative movement of the tubular plates on the cylinder is prevented by a stop rib 1^b on the cylinder. After the plates 2 are in position, the clamping plate 5 is brought 15 up against the clamps 4 and secured. This clamp plate 5 is rotatably mounted on the journal of the cylinder, and is secured thereto by means of bolts 6 tapped into the end of the cylinder and passing through curved 20 slots 5^a in the clamp plate 5. Said clamp plate is provided with inwardly projecting fingers 5^b which, after the bolts 6 are loosened, can be brought opposite the clamps 4, and, as shown in Figs. 6 and 7, can be pressed 25 inward against the clamps 4 by tightening the bolts 6, thereby causing the clamps 4 and 3 and collar 1^a to securely hold the plates in position against endwise movement.

When the plates are to be removed the 30 bolts 6 are loosened, and the clamp plate 5 turned to the position indicated in dotted lines Fig. 6, whereupon the clamps 4 can be removed; then the second plate 2 is slid endwise off the cylinder, then the clamps 3 are 35 removed and the first plate 2 slid endwise off the cylinder. In this manner the tubular plates can be readily and easily placed on or removed from the cylinder.

The advantages of the tubular plates and 40 small single-plate cylinder over the large double-plate cylinders heretofore employed are the reduction in the number of plates required; and the fact that practically no part of the rotary movement of the plate cylinder is idle; no time is wasted for collection, as is necessary with the large plate cylinders where plates are in duplicate, and the pages must be collected. My invention therefore requires a less number of plates to 45 produce the same number of pages at the same peripheral speed as the old press,—and, consequently, lessens the operative expenses. To run an old machine and print 16 pages, requires 32 plates in the ordinary two-plate 50 machine; while my machine equipped with my single plates, would require only 16 plates to print 16 pages at the same speed, the surface speed of the cylinders in both cases being equal. Further with my single 55 plate cylinders a better class of work can be produced, inasmuch as the circumference of the composition rollers can be made equal to the circumference of the plate, so that no portion of the roller would strike twice 60 in one revolution on the same plate, and it

will therefore deposit color more uniformly thereon.

Having described my invention what I claim as new and desire to secure by Letters Patent is:—

1. The combination of a plate cylinder having longitudinal grooves, with a plurality of tubular plates adapted to be successively slipped endwise on said cylinder, engaging clamps slipped in the cylinder 70 grooves between the adjacent plates, end clamps in the grooves engaging the edge of the outermost plate, and a clamp-plate engaging the end clamps.

2. The combination of a plate cylinder 80 having longitudinal grooves, a set of sliding plate clamps engaging the said grooves, a clamp ring adjustably attached to the end of the cylinder and adapted to be rotatably moved into and out of position to engage 85 the clamps, and bolts for forcing the clamping plate inward against the clamps after it is turned to engaging position.

3. The combination of a cylinder, provided with longitudinal grooves, and plate 90 clamps adjustably mounted in said grooves, tubular plates adapted to be successively slipped endwise on said cylinder, and a rotatably movable clamp plate mounted on the end of the cylinder having lugs adapted to 95 engage the outermost plate clamps, and means for forcing said clamp plate inward and causing it to force the clamps inward.

4. The combination with a cylinder, provided with longitudinal grooves, a clamp 100 collar on the cylinder, and plate clamps adjustably mounted in each of said grooves, with plates adapted to be placed on said cylinder, and a rotatable clamp plate mounted on the end of the cylinder having lugs 105 adapted to engage the outermost plate clamps when the clamp plate is turned to one position, and bolts passing through slots in the clamp plate, and whereby it is caused to force the clamps inward.

5. The combination of a plate cylinder 110 having longitudinal grooves, with tubular plates slipped endwise on said cylinder, plate clamps loosely mounted in the said grooves, a clamp ring adjustably attached to 115 one end of the cylinder and adapted to be rotatably moved into and out of position to engage the plate clamps, and means for forcing the clamping ring toward the plate clamps.

6. For a rotary cylinder printing press, a printing plate containing a single-page of type matter and curved in tubular form to leave a single narrow longitudinal slot between the adjacent ends of the plate equal 125 in width to the margin between successive impressions taken from such plate upon a web.

7. The combination of a plate cylinder, with a removable stereotype plate compris- 130

ng but one page of type matter curved in tubular form and adapted to substantially extend around the entire circumference of the cylinder, and having a narrow space between the adjacent ends of the printing surface of the plate corresponding in width to the margin between successive impressions taken from such plate upon a web, and means for detachably securing such plate on the cylinder.

8. In combination, a plate cylinder whose circumference is slightly greater in extent than the length of an ordinary newspaper type page, with a tubular stereotype plate having a narrow longitudinal slot and containing but one newspaper page of matter, and curved to substantially surround the cylinder and to be slipped endwise on and off the cylinder, and means for detachably attaching the plate to the cylinder.

9. In a newspaper printing press, the combination of a rotary plate cylinder of small diameter and whose circumference is slightly greater in extent than the length of an ordinary newspaper type page; with a printing plate equal in superficial extent to an ordinary one-page type plate, but curved to substantially surround the cylinder when slipped endwise thereon, the space between the adjacent ends of the curved plate corresponding to the margin between successive impressions taken from said plate upon a web, and means for detachably attaching the plate to the cylinder.

10. In a printing press, the combination of a plate cylinder having an annular collar at one end, a set of tubular plates each having a single longitudinal slot and adapted to substantially surround the cylinder, and to be successively slipped endwise onto the cylinder and fit closely thereto; removable clamps adapted to be interposed between

the ends of said plates, adjustable plate clamps at the end of the cylinder opposite the collar, and means for causing the latter to engage the end of the adjacent plate, substantially as described.

11. In a rotary newspaper printing press, the combination of a rotary plate cylinder having a circumference slightly greater in extent than the length of an ordinary newspaper type page; with a single-page tubular plate equal in superficial extent to an ordinary newspaper page plate and curved to practically surround the said cylinder and be slidably fitted thereupon, and means for clamping the plate endwise upon said cylinder.

12. A cylindrical tubular stereotype plate containing a single page of type matter and having a single narrow longitudinal marginal space equal in width to the desired margins between two consecutive impressions taken from such plate upon a web.

13. A cylindrical tubular printing plate for use on rotary cylinder printing presses having a single narrow longitudinal marginal space equal in width to the desired margin between two consecutive impressions taken from such plate upon a web, the plate being curved lengthwise circumferentially of the cylinder.

14. A cylindrical tubular printing plate having a single narrow longitudinal slot equal in width to the desired marginal space between consecutive impressions taken from such plate upon a web.

In testimony that I claim the foregoing as my own, I affix my signature in presence of two witnesses.

HENRY F. BECHMAN.
